UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

FRICTION SHOCK-ABSORBING MECHANISM.

Application filed January 31, 1927. Serial No. 164,885.

This invention relates to improvements in friction shock absorbing mechanisms.

One object of the invention is to provide a friction shock absorbing mechanism especially adapted for railway draft riggings including a spring cage, friction shell and friction system co-operating with the shell, the shell and cage having limited movement to provide for initial spring action, wherein the shell is of simple design, lending itself to economic manufacture and is removable to provide for replacement of the shell by another when worn.

Other and further objects of this invention will more fully and clearly appear from the description and claims hereinafter following.

In the drawings, forming a part of this specification, Figure 1 is a horizontal longitudinal sectional view of a railway draft rigging showing my improvements in connection therewith. Figure 2 is a front end elevational view of the shock absorbing mechanism proper. Figure 3 is a vertical transverse sectional view corresponding substantially to the line 3-3 of Figure 1. And Figure 4 is a longitudinal vertical sectional view of the front end portion of the shock absorbing mechanism proper corresponding substantially to the line 4-4 of Figure 1.

In said drawings, 10-10 indicate channel-shaped center or draft sills of a railway car underframe, to the inner sides of which are secured front stop lugs 11-11 and rear stop lugs 12-12. The inner end portion of the drawbar is indicated by 13, to which is operatively connected a yoke 14 of well known form. The shock absorbing mechanism proper and a front main follower 15 are disposed within the yoke, and the yoke and the parts therewithin are supported in operative position by a detachable saddle plate 16 fixed to the draft sills.

My improved shock absorbing mechanism comprises broadly: a spring cage A; a friction shell B; a wedge block C; a pair of friction shoes D and E; a main spring resistance F; and a retainer bolt G.

The spring cage A is in the form of a hollow box-like casting having a transverse end wall 17, longitudinally disposed vertical side walls 18-18 and horizontally disposed spaced top and bottom walls 19-19. The end wall co-operates with the top lugs 12

in the manner of the usual rear follower. 55 The side walls as most clearly shown in Figure 1, converge forwardly of the mechanism and terminate in front end sections 20-20 which are substantially parallel to the longitudinal axis of the mechanism. At the 60 junction between the main body portions of the side walls 18 and the front end sections 20, the side walls are provided with inwardly projecting vertically disposed stop flanges 21-21 which are adapted to co-operate with 65 the inner end of the friction shell B to limit longitudinal movement of the same inwardly of the cage.

The friction shell B is in the form of a substantially rectangular box-like member 70 open at its front and rear ends. The side walls of the friction shell which are designated by 22 are provided with interior longitudinally disposed friction surface 23-23 which co-operate with the friction shoes D 75 and E. The side walls 23 of the shell are longitudinally slotted as indicated at 24 to provide guideways for retaining elements 25-25 fixed to the spring cage, being riveted to the sections 19 of the side walls thereof. The retaining elements 25 are in the form of rivet-like members having enlarged cylindrical inner end sections 26 which work directly in the slots 24. The rivet-like retaining elements 26 extend through suitable openings 85 in the side wall sections 19 of the spring cage and have their outer ends upset so as to provide rivet heads for securing the same to the cage. It will be evident that if it is desired to replace the friction shell B when worn by a 90 new shell, the rivet-like retaining elements 25 may be readily removed by cutting off the heads of the same. The slots 24 in the side walls of the friction shell are of such a length that the enlargements 26 on the retaining elements will engage with the inner end walls of 95 the slots, thereby limiting outward movement of the friction shell and that the outer end walls of the slots will be engaged by said enlargements simultaneously with engagement 100 of the rear end of the shell B with the stop flanges 21 of the spring cage to limit inward movement of the friction shell.

Upon reference to Figure 1, it will be seen that the friction shell is loosely telescoped 105 within the front end section of the spring cage A and that in its outermost position the shell has the front end thereof registering

with the front end of the spring cage, the shell being thus entirely housed within the spring cage at all times.

The wedge C is in the form of a hollow block having a flat front end face 27 bearing directly on the inner side of the main follower 15. At the inner end, the wedge block C is provided with inwardly converging wedge faces 28 and 29 at the opposite sides thereof, 5 the wedge face 28 being herein shown as disposed at a relatively keen angle with respect to the longitudinal axis of the mechanism and the wedge face 29 being shown as disposed at a somewhat blunter angle with respect to said 10 axis.

The friction shoes D and E are disposed at opposite sides of the mechanism and are interposed between the wedge block C and the side walls of the friction shell B. The two 20 shoes D and E are of similar design except as hereinbefore pointed out. Each of the shoes is provided with a longitudinally disposed outer flat friction surface 123 adapted to co-operate with the corresponding friction surface 23 of the shell B. At the inner side, each shoe is provided with a lateral enlargement 30 having a wedge face at the forward side thereof, the wedge face on the shoe D being designated by 129 and being correspondingly inclined to the face 29 of the wedge and co-operating therewith and the wedge face of the shoe E being designated by 128 and being correspondingly inclined to the wedge face 28 of the wedge C and co-operating therewith. Rearwardly of the enlargements 30 the shoes D and E are provided with spaced, inwardly projecting top and bottom flanges 31—31 as most clearly shown in Figure 3.

40 The main spring resistance F comprises an inner, relatively light coil and an outer heavier coil. The outer coil has its opposite ends bearing directly on the inner ends of the friction shoes D and E and the end wall 17 of the spring cage. The inner coil of the spring resistance has the rear end thereof bearing on an inwardly projecting hollow boss 32 on the end wall 17. The front end of the last named coil bears on the inner ends of the enlargements 50 of the friction shoes. It will be seen that by the arrangement disclosed, an exceptionally long spring resistance element may be employed.

The retainer bolt G serves to hold the mechanism assembled and of overall uniform length, the head of the bolt being anchored within the hollow boss 32 on the end wall 17 of the cage A and the nut of the bolt being anchored to the wedge block C, the same being 60 disposed within the opening of said block. The retainer bolt G in addition to holding the parts assembled, also serves to maintain the spring resistance F under an initial compression. It will be evident that due to this 65 initial compression of the main spring resist-

ance, the same is free to expand as the friction and wedge faces of the mechanism become worn, thereby compensating for wear of these parts.

The operation of my improved shock absorbing mechanism, assuming a compression stroke, is as follows: The main follower 15 and the spring cage will be moved relatively toward each other, thereby forcing the wedge C and the friction shoes D and E inwardly of the mechanism against the resistance of the spring F. Due to the wedging action set up between the wedge block C and the shoes, the latter are forced into tight frictional engagement with the side walls of the shell B, thereby carrying the shell B inwardly of the cage A during the first part of the compression stroke of the mechanism. This action will continue until the movement of the shell B is stopped by engagement with the flanges or stop lugs 21 70 on the spring cage, whereupon the friction shoes will be forced to move on the friction surfaces of the shell during the remainder of the compression stroke, thereby greatly augmenting the resistance offered to take care of relatively heavy shocks. The described action will continue until the actuating force is reduced or the main follower 15 comes into engagement with the outer end of the spring cage, whereupon the actuating force will be 75 transmitting directly through the follower and the spring cage, these elements acting as a solid column load transmitting member to prevent undue compression of the main spring resistance and deliver the shock directly to 80 the draft sills.

When the actuating force is reduced upon release of the mechanism, the expansive action of the main spring resistance F will carry the wedge block and friction shoes outwardly, the shell B being also forced outwardly with these elements, due to the friction existing between the shoes and the shell. Outward movement of the shell will be arrested by engagement with the stop elements 25 whereupon the 85 spring resistance F will project the shoes and the wedge block C outwardly until movement of the wedge is arrested by the retainer bolt G.

From the preceding description taken in connection with the drawings, it will be evident that I have provided a friction shell of exceedingly simple construction which may be economically manufactured and readily replaced by a new shell when worn, thereby adding materially to the life of the whole gear. 90 As hereinbefore pointed out, in order to replace the friction shell B by a new shell, it is merely necessary to remove the wedge and friction shoes and then remove the rivets 25, thereby permitting the shell to be withdrawn. 95 A new shell will then be inserted and secured by rivets 25.

While I have herein shown and described what I now consider the preferred manner of carrying out my invention, the same is merely 100

illustrative, and I contemplate all changes and modifications that come within the scope of the claims appended hereto.

I claim:

- 5 1. In a friction shock absorbing mechanism, the combination with a spring cage element; of a removable friction shell element telescoped within the cage element, said elements having relative movement limited to less than 10 the full compression stroke of the mechanism; stop means on the cage element for limiting inward movement of the shell element; means for limiting outward movement of the shell element, said means including a fixed pin on 15 one of said elements working in a slot on the other element; friction means co-operating with the shell; and spring resistance means within the cage co-operating with the friction means.
- 20 2. In a friction shock absorbing mechanism, the combination with a spring cage; of a friction shell telescoped within the spring cage; means for limiting movement of the shell inwardly of the cage before the mechanism has been fully compressed; means for 25 limiting outward movement of the friction shell and maintaining said shell housed with-

in the spring cage; friction means co-operating with the shell and adapted for movement with respect thereto; and means for yielding- 30 ly resisting movement of said friction means inwardly of the cage.

3. In a friction shock absorbing mechanism, the combination with a spring cage having a square section at one end thereof; of a rectangular friction shell telescoped within said square end section of the cage; stop shoulders on the cage for arresting inward movement of the shell after a predetermined compression of the mechanism; a pair of friction shoes 40 co-operating with the shell and movable relatively thereto after movement of the shell has been arrested; a wedge block having wedging engagement with the shoes; means for limiting outward movement of the shell, 45 including stop elements fixed to the cage and engaging within limiting slots in the shell; and spring resistance means opposing movement of the shoes and shell inwardly of the cage.

In witness that I claim the foregoing I have hereunto subscribed my name this 26th day of January, 1927.

JOHN F. O'CONNOR.
